(57) **CLAIM**

The ornamental design for a self-balancing scooter with translucent deck, as shown and described.

DESCRIPTION

FIG. 1 is a front perspective view of a self-balancing scooter with translucent deck showing my new design;

FIG. 2 is a front elevation view thereof;

FIG. 3 is a rear elevation view thereof;

FIG. 4 is a top view thereof;

FIG. 5 is a bottom view thereof;

FIG. 6 is a left side elevation view thereof; and,

FIG. 7 is a right side elevation view thereof.

The dotted lines represent portions of the self-balancing scooter with translucent deck that form no part of the claimed design.
